Primary Examiner — Mark Goodwin(74) *Attorney, Agent, or Firm* — The Webb Law Firm(57) **CLAIM**

The ornamental design for a front cover of engine hood for work machine, as shown and described.

DESCRIPTION

FIG. 1 is a front view of a front cover of engine hood for work machine showing my new design;
 FIG. 2 is a rear view thereof;
 FIG. 3 is a left side view thereof;
 FIG. 4 is a right side view thereof;
 FIG. 5 is a top view thereof;
 FIG. 6 is a bottom view thereof; and,
 FIG. 7 is an upper front right side perspective view thereof.
 The portions of the front cover of engine hood for work machine shown in broken lines form no part of the claimed design.
